(74) Attorney, Agent, or Firm — Wolf, Greenfield &
Sacks, P.C.

(57) **CLAIM**

The ornamental design for a three dimensional mastopexy implant, as shown and described.

DESCRIPTION

FIG. 1 is a top, front, side perspective view of a three dimensional mastopexy implant showing our new design; FIG. 2 is a front view of the three dimensional mastopexy implant shown in FIG. 1; FIG. 3 is a rear view of the three dimensional mastopexy implant shown in FIG. 1; FIG. 4 is a first side view of the three dimensional mastopexy implant shown in FIG. 1; FIG. 5 is a second side view of the three dimensional mastopexy implant shown in FIG. 1; FIG. 6 is a top view of the three dimensional mastopexy implant shown in FIG. 1; FIG. 7 is a bottom view of the three dimensional mastopexy implant shown in FIG. 1; and, FIG. 8 is an enlarged view of the mesh taken from FIG. 1.

1 Claim, 8 Drawing Sheets
